[57] ABSTRACT

A thickness control apparatus for a rolling mill in which the output thickness of a moving web or strip is changed by changing the set value of the thickness of the rolling material from a specific point, and said thickness control apparatus is characterized in that the thickness of the rolling material is changed at the first stand, and the tension of the web or strip is controlled in the rest of the stands.

FIG. 2

THICKNESS CONTROL APPARATUS FOR ROLLING MILL

BACKGROUND OF THE INVENTION

The present invention relates to automatic thickness control systems for changing the set value of the output thickness of a moving web or strip in the rolling mill.

The multi-stand rolling mill, in the prior art, provides from a rolling material a web or strip having a specific thickness. With an increasing demand for more varied rolling products in recent years, the rolling mill has been required to have greater capacity and higher efficiency and to be capable of providing a wide range of products.

In the prior art, however, time-consuming procedures are required for changing the parameters set for the rolling mill when a different rolling product is desired. To change the set values, therefore, the rolling efficiency must be sacrificed. Furthermore, once rolling has started, it must be continued to the end of the material being rolled. This makes it difficult to obtain a specific length of web or strip during one operation.

SUMMARY OF THE INVENTION

In view of the foregoing, a general object of this invention is to provide a thickness control apparatus capable of accurately and quickly changing the thickness of a rolling web or strip.

Briefly, according to the present invention, the coefficient affecting the output thickness of a moving web or strip produced by changing independently the roll gaps in the individual stands and the coefficient affecting the tension thereof in each stand are found by measurement or logical equations, the roll gap variation in each stand is calculated according to said coefficients, thus permitting the output thickness of the web or strip and the tension thereof in each stand to be set at the desired values, and the roll gap of each stand is changed each time the thickness changing point reaches the respective stand.

More specifically, the change of the final output thickness is determined almost entirely by the roll gap change in the first stand, the roll gaps of the other stands being changed mainly by changing the tension thereof. The roll gap of the first stand is controlled according to the set value of the final output thickness, and the other roll gaps are controlled according to the set value of the tension adapted to the final output thickness.

Thus, according to the invention, a rolling mill is provided which is capable of continuously producing a product with different thicknesses.

BRIEF DESCRIPTION OF THE DRAWING

FIG. 1 is a block diagram illustrating an apparatus embodying this invention; and

FIGS. 2 (a) through 2(e) are graphic representations illustrating the shapes of a rolling web or strip in the vicinity of the thickness changing point in each stand shown in FIG. 1.

DESCRIPTION OF THE PREFERRED EMBODIMENT

Assume that the final output thickness h_f of the roll gap of the ith stand and the tension t_{bi} on the uncoiler side of the ith stand are changed. The final output thickness changing values ($\Delta h_f/h_f$) can be obtained by summing the products of the changing values ΔS_i of the roll gaps of the ith stand and the coefficients a_i affecting the final output thickness in the ith stand. In general, the changing value ($\Delta h_f/h_f$) is expressed as

$$15 \quad \frac{\Delta h_f}{h_f} = \sum_{i=1}^n \Delta S_i \cdot a_i \quad (1)$$

where n designates the number of stands. When n is 5 in the rolling mill,

$$20 \quad \Delta h_f/h_f = a_1 \Delta S_1 + a_2 \Delta S_2 + a_3 \Delta S_3 + a_4 \Delta S_4 + a_5 \Delta S_5 \quad (2)$$

The changing value ($\Delta h_f/h_f$) on the uncoiler side of the jth stand can be obtained by summing the products of the changing value ΔS_i of the roll gap of the ith stand and the coefficient b_{ji} affecting the tension in the jth stand. For example,

$$25 \quad \frac{\Delta t_{bj}}{t_{bi}} = \sum_{i=1}^n b_{ji} \cdot \Delta S_i \quad (j=1, 2, \dots, n-1, n) \quad (3)$$

From equation (3), the changing values in the five stands are given as

$$30 \quad \Delta t_{b1}/t_{b1} = b_{11} \Delta S_1 + b_{12} \Delta S_2 + b_{13} \Delta S_3 + b_{14} \Delta S_4 + b_{15} \Delta S_5 \quad (4)$$

$$35 \quad \Delta t_{b2}/t_{b2} = b_{21} \Delta S_1 + b_{22} \Delta S_2 + b_{23} \Delta S_3 + b_{24} \Delta S_4 + b_{25} \Delta S_5 \quad (5)$$

$$\Delta t_{b3}/t_{b3} = b_{31} \Delta S_1 + b_{32} \Delta S_2 + b_{33} \Delta S_3 + b_{34} \Delta S_4 + b_{35} \Delta S_5 \quad (6)$$

$$\Delta t_{b4}/t_{b4} = b_{41} \Delta S_1 + b_{42} \Delta S_2 + b_{43} \Delta S_3 + b_{44} \Delta S_4 = b_{45} \Delta S_5 \quad (7)$$

$$\Delta t_{b5}/t_{b5} = b_{51} \Delta S_1 + b_{52} \Delta S_2 + b_{53} \Delta S_3 + b_{54} \Delta S_4 + b_{55} \Delta S_5 \quad (8)$$

In the ordinary rolling mill where a constant tension control device is used on the uncoiler side as well as on the coiler side, the tension changing value ($\Delta t_{bi}/t_{bi}$) on the uncoiler side of the first stand and the tension changing value ($\Delta t_{b5}/t_{b5}$) on the coiler side of the fifth stand are nearly equal to zero.

40 The thickness changing method of this invention will be described below based on equations (2) and (4) through (8).

Substituting the final output thickness changing value for Δh_f of equation (2), and the tension changing value for t_b of equations (4) through (8), and solving the simultaneous equations (2) and (4) through (8) with five unknowns, the roll gap changing values $\Delta S_1, \Delta S_2, \Delta S_3, \Delta S_4, \Delta S_5$ of the individual stands can be determined as set values changed for the final output thickness and tension. To find the roll gap changing value from the above equations, it is necessary to obtain coefficients. Tables 1 and 2 show the necessary coefficients obtained according to measurements on a five-stand rolling mill.

TABLE 1

	Ratio of Final Output Thickness Changing Values				
	1st stand ($\Delta h_f/h_f$)	2nd stand	3rd stand	4th stand	5th stand
65	0.1565	0.0273	-0.0019	-0.0000	0.0184

Note: The roll gaps of individual stands are changed independently by 1 mm. The width of the web or strip produced is 930 mm and the thickness is changed from 2.0 to 0.4mm.

TABLE 2

1st stand	2nd stand	3rd stand	4th stand	5th stand	Ratio of Uncoiler Side Tensions
$(\Delta t_{b1}/t_{b1})$	0	0	0	0	
$(\Delta t_{b2}/t_{b2})$	-0.380	1.027	-0.074	0.007	-0.001
$(\Delta t_{b3}/t_{b3})$	-0.236	0.084	0.739	-0.076	0.016
$(\Delta t_{b4}/t_{b4})$	-0.182	-0.030	0.094	0.480	-0.105
$(\Delta t_{b5}/t_{b5})$	-0.230	-0.045	-0.005	0.139	0.526

Note: The roll gaps of individual stands are changed independently by 1 mm. The width of the web or strip produced is 930 mm and the thickness is changed from 2.0 to 0.4 mm.

Table 1 shows the ratio of the final output thickness changing values under the condition that the roll gaps of individual stands are changed independently from each other. In the above example, the roll gap changing value in each stand is 1 mm, or in other words, the roll gap changing value provides the coefficient affecting the final output thickness of each stand. For example, the coefficient a_1 affecting the final output thickness in the first stand is 0.1565. While Table 2 shows the ratio of the uncoiler side tension under the condition that the roll gaps of individual stands are changed independently. In this case, the roll gap changing value of each station is 1 mm. Hence, this roll gap indicates the coefficient b_{ji} affecting the uncoiler side tension in the jth stand. For example, the coefficient b_{32} affecting the uncoiler side tension in the third stand due to the roll gap change in the second stand is 0.084.

In Table 2, the values b_{ji} are provided at the intersection of the ith stand column and the $(\Delta t_{bj}/t_{bj})$ row. If the coefficients can be obtained in the manner as shown in Tables 1 and 2, then an ideal roll gap changing value in each station can be found through the foregoing equations. It is apparent from Table 1 that the coefficient a affecting the final output thickness at the change of the roll gap in the first stand is far greater than those in other stands.

Table 2 indicates that the coefficients b_{ji} ($b_{21}, b_{31}, b_{41}, b_{51}$) affecting the uncoiler side tensions in the stands, except the first stand, and the coefficients b_{ji} ($b_{22}, b_{33}, b_{44}, b_{55}$) affecting the uncoiler side tensions in the stands, except the first stand, are great. On the contrary, the coefficients affecting the other uncoiler tensions are very small. By utilizing this principle, the foregoing equations are simplified; namely, equation (1) is rewritten

$$\Delta h_F/hF = a_1 \Delta S_1 \quad (1)$$

Similarly, equation (3) is

$$\Delta t_{bj}/t_{bj} = b_{ji} \Delta S_1 + b_{jj} \Delta S_j \quad (3)$$

Equations (2) and (5) through (8) can be expressed as

$$\Delta hF/hF = a_1 \Delta S_1 \quad (2)$$

$$\Delta t_{b2}/t_{b2} = b_{21} \Delta S_1 + b_{22} \Delta S_2 \quad (5)$$

$$\Delta t_{b3}/t_{b3} = b_{31} \Delta S_1 + b_{33} \Delta S_3 \quad (6)$$

$$\Delta t_{b4}/t_{b4} = b_{41} \Delta S_1 + b_{44} \Delta S_4 \quad (7)$$

$$\Delta t_{b5}/t_{b5} = b_{51} \Delta S_1 + b_{55} \Delta S_5 \quad (8)$$

In order to change the final output thickness by Δh_f so as to obtain the specified value of tension in each stand, the roll gap of each stand must satisfy the following equations.

$$\Delta S_1 = 1/a_1 \cdot \Delta h_f/h_f \quad (9)$$

$$S_2 = 1/b_{22} \cdot t_{b2}/t_{b2} - b_{21}/b_{22} \Delta S_1 \quad (10)$$

$$S_3 = 1/b_{33} \cdot t_{b3}/t_{b3} - b_{31}/b_{33} \Delta S_1 \quad (11)$$

$$S_4 = 1/b_{44} \cdot t_{b4}/t_{b4} - b_{41}/b_{44} \Delta S_1 \quad (12)$$

$$S_5 = 1/b_{55} \cdot t_{b5}/t_{b5} - b_{51}/b_{55} \Delta S_1 \quad (13)$$

In the above equations, $\Delta t_{b2}/t_{b2}$, $\Delta t_{b3}/t_{b3}$, $\Delta t_{b4}/t_{b4}$, $\Delta t_{b5}/t_{b5}$ are determined to be suitable according to the changing value of the final output thickness. These values can be found from measurement and logical equations. When the change Δh_f of the final output thickness is small, $\Delta t_{b2}/t_{b2}$, $\Delta t_{b3}/t_{b3}$, $\Delta t_{b4}/t_{b4}$ and $\Delta t_{b5}/t_{b5}$ can be reduced to zero. In this case, equations (9) through (13) are rewritten as follows.

$$\Delta S_1 = 1/a_1 \cdot \Delta hF/hF \quad (14)$$

$$\Delta S_2 = -(b_{21}/b_{22}) \Delta S_1 \quad (15)$$

$$\Delta S_3 = -(b_{31}/b_{33}) \Delta S_1 \quad (16)$$

$$\Delta S_4 = -(b_{41}/b_{44}) \Delta S_1 \quad (17)$$

$$\Delta S_5 = -(b_{51}/b_{55}) \Delta S_1 \quad (18)$$

From equations (14) through (18), it is apparent that the roll gap is changed so that the final output thickness is changed by changing the first stand roll gap, and the tension change caused by said roll gap changed is absorbed by another roll gap change.

To change the roll gap based on the above equations, it is necessary to change the roll gap sequentially from the stand reaching the thickness changing point. Thus, a speedy and accurate thickness change can be realized.

The invention will be more specifically described with reference to the accompanying drawings.

Referring to FIG. 1, there is shown an embodiment of this invention applied to a five-stand rolling mill, which includes stands 1 through 5 of the rolling mill, a thickness detector 10, roll screw down devices 11 through 15, motors 21 through 25 for driving the roll screw down devices 11 through 15, speed controllers 31 through 35 for the individual stands, speed detectors 41 through 45 for the individual stands, a material detector 50, thickness changing point detectors 61 through 65 for detecting the presence of the thickness changing point as it reaches each stand and for instructing the roll gap change for the corresponding stand, gate circuits 71 through 75, moving signal calculators 81 through 85 for calculating the moving signal Δm_i thereby operating the roll screw down devices according to the roll gap changing value ΔS_i , gap calculators for calculating the roll gap changing value ΔS_i , gap calculators 91 through 95 for calculating the roll gap changing value ΔS_i , a roll down controller 100 of the first schedule for calculating the moving signal Δm_i of the roll screw down device driving motors in order to find the thickness before it is changed (namely, the first schedule thickness), a coefficient memory 110 for finding the roll gap changing value in each stand in order to obtain the thickness of another schedule, and a coefficient correcting device 120 for finding the coefficient from the actual thickness and tension and for correct-

ing the value of the coefficient memory in the next control. The reference 130 represents a tension changing value memory for storing the tension changing value adapted to the changing value of the final output thickness for the purpose of obtaining the tension thereof in each stand, conforming to the final thickness set value. Elements 200 through 202 are input terminals, and element 203 is an input terminal for receiving an uncoiler side tension input for each stand.

A thickness value which may most frequently be required in the rolling mill, or a thickness value which is suitable for use as a standard is chosen from among popular thickness values. Such a thickness value is used as a standard, and the roll gap value of each stand corresponding to the standard thickness is stored in the roll down controller 100. The roll gap is set according to this standard thickness, and the roll speed is set by the speed controllers (31 through 35) of each stand. Then, rolling starts.

When the tip end of the rolling material reaches the first stand, the material detector 50 located on the input side of the first stand starts generating an output signal. By means of this signal, the detected value V_1 of the first stand speed detector 41 is supplied to the first stand thickness changing point detector 61. The thickness changing point detector 61 of the first stand calculates the length of the rolling material passing through the first stand according to the roll speed value V_1 . When the length thereof reaches a specific value set via the input terminal 200, namely when the thickness changing point reaches the first stand, the detector 61 starts generating an output signal. While, on the other hand, the difference ΔhF between the final output thickness value hF in the existing schedule and the value hF' in the following schedule is applied to the gap calculator 91 via input terminal 202. To the gap calculators 91 through 95, necessary coefficients are applied from the coefficient correcting device 110, and also the tension changing values adapted to the final output thickness Δh_f are applied from the tension changing value memory 130. The gap calculators 91 through 95 calculate gaps according to equations (9) through (13), and supply the roll gap changing values ΔS_i to the moving signal calculators 81 through 85.

It is assumed that the tension of each stand is not changed when Δh_f is comparatively small. If this is so, ΔS_i is obtained according to equations (14) through (18). In such a case, the tension changing value memory 130 is not required. Then, the operating signals Δm_1 , Δm_2 , Δm_3 , Δm_4 and Δm_5 to be sent to the motors 21 through 25 are calculated by the moving signal calculators 81 through 85.

When the thickness changing point reaches the first stand, and the thickness changing point detector 61 starts generating an output signal, the gate 71 is opened. By this means, Δm_1 is supplied to the motor 21 to operate the roll screw down device 11, thereby changing the first stand roll gap by ΔS_i . By means of the output signal of the thickness changing point detector, the second stand roll speed value V_2 is delivered from the speed detector 42 to the second stand thickness changing point detector 62. In the same manner, when the thickness changing point reaches the ith stand, the thickness changing point detector generates an output signal. By this means, Δm_i is supplied to the motor to

operate the roll screw down device, thus changing the roll gap of the ith stand by ΔS_i . In other words, the thickness change is finally completed at the instant the thickness changing point passes through the fifth stand.

According to the embodiment as illustrated in FIG. 1, the feed of the material into the first stand is detected by the material detector 50, the material with a specific thickness is rolled to a length being set via the input terminal 200, and the material thickness is changed automatically to the value set for the next stand. Namely, by supplying the input terminal 200 with the value set for the next stand. Namely, by supplying the input terminal 200 with the value of length to each thickness changing point in succession, the thickness is automatically changed when the material is fed to the set length.

Instead of the thickness changing point detector 61 and material detector 50, other means may be employed wherein the thickness changing signal is applied to the thickness changing point detector 62 and the gate circuit 71 is opened whereby the thickness can be changed to a desired value.

According to this invention, the coefficient at which the final output thickness is changed and the coefficient at which the tension in each stand is changed with change of the gap of each stand are obtained, while on the other hand, the difference between the standard final output thickness and the desired thickness, and also the tension in each station adapted to the thickness are supplied thereto whereby the roll gap value of each station is obtained and thus the rolling thickness is quickly changed.

The accuracy of the rolling mill is increased in the following manner. The final thickness is detected by the thickness detector 10, the coefficient a_1A affecting the final output thickness at the change of the roll gap of the first stand is calculated by the coefficient correcting device 120 according to said detected final thickness, and the subsequent change in thickness is accomplished by using the coefficient a_1A . The coefficient a_1A is obtained by the following equation.

$$a_1A = (hF - hF'/hF^{-1}) (1/\Delta S_i) \quad (19)$$

where hF is the final output thickness after thickness change,

hF^{-1} is the final output thickness before thickness change, and

ΔS_i is the first stand roll gap changing value.

The value a_1A obtained by equation (19) includes an external disturbance. To smooth the value a_1A , the following equation is used.

$$a'_1A = a'_1 + \sigma(a_1A - a'_1) \quad (20)$$

where a'_1A is the coefficient after smoothing,

a'_1 is the coefficient adapted and corrected in the previous schedule,

σ is a constant, and

a_1A is the coefficient obtained by equation (19).

Similarly, from equations (10) through (13), the values b_{22} , b_{33} , b_{44} and b_{55} are found by the use of the coefficient correcting device, to change the value of the coefficient memory. Instead of the operation using the detected value supplied from the thickness detector 10, the tension value of each stand is given to the input terminal 203 whereby Δt_i ($i=2-5$) is calculated. In this case, the values b_{21} , b_{31} , b_{41} and b_{51} are not changed. The standard tension values t_{b2} , t_{b3} , t_{b4} and t_{b5} are inde-

pendently set and not changed. The value ΔS_i ($i=2-5$) is applied from each of the gap calculators 92 through 95 to the coefficient correcting device. By the above arrangement and procedures, the accuracy of a rolling mill can further be increased.

FIGS. 2(a) through 2(e) show the shapes of the rolling material in the vicinity of the thickness changing point in the thickness changing control according to this invention. It is apparent from the figure that the material is rolled perfectly to the desired thickness except for the area in the vicinity of the thickness changing point. In short, the invention makes it possible to realize a continuous thickness change of the rolling material with a high accuracy and at a high speed, and thus, to reduce the time involved in the rolling operation and to minimize the rolling efficiency.

While we have shown and described one embodiment in accordance with the present invention, it is understood that the same is not limited thereto but is susceptible of numerous changes and modifications as known to a person skilled in the art, and we therefore do not wish to be limited to the details shown and described herein but intend to cover all such changes and modifications as are obvious to one of ordinary skill in the art.

We claim:

1. A thickness control apparatus for a multi-stand rolling mill in which the thickness of a moving web is changed from a first value to a second value at a certain specific point on the moving web, comprising detecting means for detecting a thickness changing point at each roll stand, gap calculator means for calculating the roll gap changing values for the respective stands according to a coefficient affecting a final output thickness due to the roll gap change in each stand and also a coefficient affecting the tension in each stand due to said roll gap change, the coefficient affecting the final output thickness and the coefficient affecting the tension in each stand being provided by independently changing the roll gaps in the individual stands, and thickness control means for changing the roll gap at each roll stand according to the roll gap changing value provided from said gap calculator means.

2. A thickness control apparatus as defined in claim 1, wherein said detecting means includes speed detecting means at each roll stand and first means at the first roll stand responsive to an input signal indicating the length of web to be rolled at a standard thickness and the output of said speed detecting means at the first roll stand for generating an output for effecting actuation of said thickness control means at the first roll stand by said gap calculator means.

3. A thickness control apparatus as defined in claim 2, wherein said detecting means includes second means at each roll stand subsequent to said first roll stand responsive to the output of the detecting means at the previous roll stand and the speed detecting means of the respective roll stand for effecting actuation of said thickness control means of the respective roll stand by said gap calculator means when said specific point on the moving web reaches that roll stand.

4. A thickness control apparatus for a multi-stand rolling mill in which the thickness of a moving web is changed from a first value to a second value at a specific point on the moving web, comprising

detecting means for detecting the thickness changing point at each roll stand, thickness control means for controlling the roll gap at each roll stand in response to respective gap control signals,

roll down control means for providing standard gap control signals for the respective roll stands,

gap calculator means responsive to an input gap changing value signal for generating changing value gap control signals including memory means for storing predetermined thickness and tension coefficient values for calculating said changing value gap control signals in accordance with said input gap changing value signal, the thickness and tension coefficient values being provided by changing the roll gap for the respective roll stands independently,

summation means for summing the respective standard gap control signals and changing value gap control signals to produce said gap control signals applied to said thickness control means, and gate means associated with each roll stand and responsive to a respective output from said detecting means indicating presence of said changing point at the respective roll stand for applying the changing value gap control signal of the respective roll stand to said summation means.

5. A thickness control apparatus as defined in claim

30 4, wherein said detecting means includes speed detecting means at each roll stand and first means at the first roll stand responsive to an input signal indicating the length of web to be rolled at a standard thickness and the output of said speed detecting means at the first roll stand for generating an output for effecting actuation of said thickness control means at the first roll stand by said gap calculator means.

6. A thickness control apparatus as defined in claim

40 5, wherein said detecting means includes second means at each roll stand subsequent to said first roll stand responsive to the output of the detecting means at the previous roll stand and the speed detecting means of the respective roll stand for effecting actuation of said thickness control means of the respective roll stand by said gap calculator means when said specific point on the moving web reaches that roll stand.

7. A thickness control apparatus as defined in claim

50 6, including thickness detector means located at the output of the last roll stand for detecting the thickness of said web, said gap calculator means further including coefficient correction means responsive to the output of said thickness detector means, said changing value gap control signals, and said input gap changing value for correcting the predetermined thickness and tension values stored in said memory means.

8. A thickness control apparatus as defined in claim

7, wherein said gap calculator means further includes tension changing value memory means for storing tension changing values adapted to the changing value of the final output thickness of said moving web.

9. A thickness control apparatus as defined in claim

4, including thickness detector means located at the output of the last roll stand for detecting the thickness of said web, said gap calculator means further including coefficient correction means responsive to the output of said thickness detector means, said changing value

gap control signals, and said input gap changing value for correcting the predetermined thickness and tension values stored in said memory means.

10. A thickness control apparatus for a multi-stand rolling mill in which the thickness of a moving web is changed from a first value to a second value at a certain specific point on the moving web comprising roll speed detectors disposed at each of the individual stands, detector means for detecting the thickness changing point at each roll stand according to the roll speed detected by said roll speed detector, gap calculator means in which the first stand roll gap changing value is calculated by the coefficient affecting the final output thickness thereof due to the roll gap change in the first stand and the roll gap changing values in the stands subsequent to the first stand are calculated by using the roll gap changing value in the first stand and the coefficient affecting the uncoiler side tension in the stands subsequent to the first stand, and roll gap controller means for controlling the roll gaps of the stand in response to control from said thickness changing point detecting means according to the roll gap changing values provided from said gap calculator means.

11. A thickness control apparatus as defined in claim 10, including thickness detector means located at the output of the last roll stand for detecting the thickness of said web, said gap calculator means including memory means for storing predetermined thickness and tension coefficient values for each roll stand and coefficient correction means responsive to the output of said thickness detector means and the roll gap changing values for correcting said predetermined thickness and tension values stored in said memory means.

12. A thickness control apparatus as defined in claim 11, wherein said gap calculator means further includes tension changing value memory means for storing tension changing values adapted to the changing value of the final output thickness of said moving web.

13. A thickness control apparatus as defined in claim 1, wherein the gap calculator means and the thickness control means serve for changing the thickness of the moving web from the first value to the second value by substantially changing the roll gap of the first roll stand to provide for a substantial change in thickness of the web and for changing the roll gaps of the other roll stands to substantially control the tension of the web.

14. A thickness control apparatus as defined in claim 13, wherein the gap calculator means and the thickness control means change the roll gap of the first stand in accordance with a set value of the final output thickness of the web and change the roll gaps of the other stands in accordance with a set value of the tension adapted to the final output thickness of the web.

15. A thickness control apparatus as defined in claim 4, wherein the gap calculator means and the thickness control means serve for changing the thickness of the moving web from the first value to the second value by

substantially changing the roll gap of the first roll stand to provide for a substantial change in thickness of the web and for changing the roll gaps of the other roll stands to substantially control the tension of the web.

5 16. A thickness control apparatus as defined in claim 12, wherein the gap calculator means calculates a roll gap changing value for each roll stand in accordance with the equations

$$\Delta S_1 = 1/a_1 \cdot \Delta h_f/h_f$$

$$\Delta S_2 = 1/b_{22} \cdot \Delta t_{b2}/t_{b2} - (b_{21}/b_{22}) \Delta S_1$$

$$\Delta S_3 = 1/b_{33} \cdot \Delta t_{b3}/t_{b3} - b_{31}/b_{33} \Delta S_1$$

$$\Delta S_i = 1/b_{ii} \cdot 66 t_{bi}/t_{bi} - b_{ii}/b_{ii} \Delta S_1$$

where $\Delta h_f/h_f$ is the final output changing value,

ΔS_i is the roll gap change value for the i th stand,

a_i is the coefficient affecting the final output thickness for the i th stand,

$\Delta t_{bi}/t_{bi}$ is the tension changing value for the i th stand, b_{ii} is the coefficient affecting tension in the i th stand due to roll gap change in the first stand, and

b_{ii} is the coefficient affecting tension in the i th stand due to roll gap change in the i th stand.

20 17. A thickness control apparatus as defined in claim 12, wherein the gap calculator means calculates a roll gap changing value for each roll stand in accordance with the equations

$$\Delta S_1 = 1/a_1 \cdot \Delta h_f/h_f$$

$$\Delta S_2 = -b_{21}/b_{22} \Delta S_1$$

$$\Delta S_3 = -b_{31}/b_{33} \Delta S_1$$

$$\Delta S_i = -b_{ii}/b_{ii} \Delta S_1$$

25 where $\Delta h_f/h_f$ is the final output changing value,

ΔS_i is the roll gap change value for the i th stand,

a_i is the coefficient affecting the final output thickness for the i th stand,

b_{ii} is the coefficient affecting tension in the i th stand due to roll gap change in the first stand, and

b_{ii} is the coefficient affecting tension in the i th stand due to roll gap change in the i th stand.

30 18. A thickness control apparatus as defined in claim 12, wherein the coefficient correcting means corrects the predetermined thickness coefficient values in accordance with the equations

$$a_1 A = hF - hF^{-1}/hF^{-1} \cdot 1/\Delta S_1$$

35 where $a_1 A$ is the corrected thickness coefficient value, hF is the final output thickness after thickness change,

hF^{-1} is the final output thickness before thickness change, and

ΔS_1 is the first stand roll gap changing value.

40 19. A thickness control apparatus as defined in claim 18, wherein the coefficient correcting means includes means for smoothing the corrected thickness coefficient value in accordance with the equation

$$a'_1 A = a'_1 + \sigma (a_1 A - a'_1)$$

45 where $a'_1 A$ is the coefficient after smoothing,

a'_1 is the coefficient adapted and corrected in the previous schedule, and

σ is a constant.
